ATTORNEY'S

UNITED STATES PATENT OFFICE

HARRY D. FORSE, OF ANDERSON, INDIANA

AUTOMATICALLY ILLUMINATED PRESSING MACHINE

Application filed April 19, 1930. Serial No. 445,557.

This invention relates to automatic illumination system forming an integral part of a commercially acceptable garment pressing machine.

- 5 55 The chief object of the invention is to equip a so-called garment pressing machine with a source of illumination and have the same arranged so that it will direct the light rays onto the garment when the pressing element 10 is elevated so that the operator can clearly see the garment and the condition thereof and which illumination is further arranged to be discontinued at such time as the pressing element 15 is in the pressing position and which 15 system of illumination is further arranged so that the illumination may be entirely disconnected from the source of energy when desired.

20 60 This invention is a continuation in part of the co-pending application Serial No. 318,774 filed Nov. 12, 1928, entitled Pressing machine.

65 The full nature of the invention will be understood from the accompanying drawings and the following description and claims.

25 70 Fig. 1 is a side elevational view of a garment press provided with a plurality of sources of illumination arranged to illuminate a garment while on the press. Fig. 2 is a wiring diagram of connections.

30 75 In the drawings 10 indicates the frame of a garment press, 11 the supporting table, 12 the buck and 13 the head supported as at 14 by the pivotally mounted arms 15 terminating in a handle portion 16 and pivotally supported as at 17 upon the upwardly extending bracket members or uprights 18.

40 80 The arms 15 and the uprights 18 each support one element of a switch construction. Herein one element is indicated by the numeral 19 and the other and movable element is indicated by the numeral 20, said elements being so arranged that when the presser element or head is elevated the arm 20 will be tilted into full line position from the dotted line position and close an electrical circuit. In Fig. 2 the handle of the switch is indicated by the numeral 20 and the switch is normally constrained toward open position and is moved to closed position which corresponds 45 85 to the full line position shown in Fig. 1 by

engagement with the abutment 19 positioned adjacent thereto.

55 90 In the preferred form of the invention the source of illumination is preferably supported by the tiltable presser element and it may be supported by either the head supporting arms 15 or the head 13 and the light may be positioned forwardly of the head and directed rearwardly or rearwardly of the head and directed forwardly. 21 indicates the reflector associated with a light source 22 which is controlled by a switch 23, the light source or bulb 22 not being shown in Fig. 1 but being shown in Fig. 2. The aforesaid is supported by bracket arms 24 on the forward side of the head and directs the light rays rearwardly.

95 95 A similar illumination structure is indicated by the numeral 25 and includes the light source 26 controlled by switch 27 and supported by bracket arms 28 connected by the forward portions of the lever arms 15. In both of the foregoing instances the reflectors 21 or 25, or both, are arranged to direct light rays rearwardly into the space between the buck and head and to illuminate the surface of the buck for garment illumination while the latter is thereon and the head is elevated.

100 100 If desired, another reflector 29, associated with a light source 30 controlled by a switch 31, may be similarly supported on the head by the bracket arms 32 and arranged to direct the light rays forwardly and onto the buck and the garment supported thereby. A similar reflector 33 associated with a light source 34 controlled by switch 35, is similarly positioned but in this instance is supported by the bracket arms 36 carried by the arms 15. In both instances the reflectors 29 and 33 are arranged to direct the light rays forwardly and to illuminate the surface of the buck or the garment thereon when the head is elevated.

105 105 If it is not desired to have the movable element support the light source, the light source may be supported in fixed relation but arranged, nevertheless, to illuminate the surface of the buck when the head or presser element is elevated therefrom. In this form of

the invention the reflector 37 is associated with a light source 38 controlled by a switch 39 and said light source is supported by bracket arms 40 carried by the uprights 18.

Since it is desirable not to employ illumination during the interval while the head is pressing on the buck, for illumination is not required at that time, the switch 19 and 20 is arranged so that the circuit to all or any of the lamps 22, 26, 30, 34 and/or 38, is closed only when the head is elevated. If any one or all of the lights are not to be illuminated, the latter condition being at the time when the press is not in operation, each of the individual switches 23, 27, 31, 35 and 39, may be opened and these switches are preferably associated with the light bulb socket in association with the respective reflectors. If desired, a common master control switch 50 may be employed which simultaneously open the circuit to all of the lamps and is independent of the lever arm movement.

The reason for illustrating a plurality of light sources is that for certain work it is imperative that no shadows fall upon the garment and while in ordinary operation but a single light source would be required, that is, for operating upon dark suits and the like; for operating upon lighter suits, a plurality of light sources may be required to be energized in order to provide sufficient illumination thereon. Likewise if light, frail garments, particularly women's dresses and the like, are to be cleaned and pressed on the garment press, it is essential that sufficient illumination be directed on to the garment and without any shadow effect, and for this purpose substantially all of the various sources of illumination illustrated may be required.

The invention claimed is:

1. In a garment press the combination of a relatively stationary pressing element, a relatively movable pressing element, a source of illumination arranged to illuminate the surface of the lower pressing element, and means automatically operable in the relative movement of the two presser elements for automatically energizing the source of illumination when the pressing elements are separated.

2. In a garment press the combination of a relatively stationary pressing element, a relatively movable pressing element, a plurality of sources of illumination arranged to illuminate the surface of the lower pressing element, and means automatically operable in the relative movement of the two presser elements for automatically energizing the sources of illumination when the pressing elements are separated.

3. The combination with a pressing machine including the usual lower presser block, upon which a garment, to be pressed is laid,

and the usual upper presser block, of an electrical source of illumination movable with the upper block and positioned to direct its rays onto the surface of the lower presser block.

4. In a garment press the combination of a relatively stationary pressing element, a relatively movable pressing element, a source of illumination arranged to illuminate the surface of the lower pressing element, and means automatically operable in the relative movement of the two presser elements for automatically energizing the source of illumination when the pressing elements are separated, said source of illumination being stationarily supported and arranged to illuminate the relatively stationary pressing element when the movable pressing element is removed from pressing position.

5. In a garment press the combination of a relatively stationary pressing element, a relatively movable pressing element, a source of illumination arranged to illuminate the surface of the lower pressing element, and means automatically operable in the relative movement of the two presser elements for automatically energizing the source of illumination when the pressing elements are separated, said source of illumination being positioned rearwardly of the two pressing elements and arranged to direct the rays forwardly and downwardly onto the relatively stationary presser element.

6. In a garment press the combination of a relatively stationary pressing element, a relatively movable pressing element, a source of illumination arranged to illuminate the surface of the lower pressing element, and means automatically operable in the relative movement of the two presser elements for automatically energizing the source of illumination when the pressing elements are separated, said source of illumination being positioned rearwardly of the two pressing elements and arranged to direct the rays forwardly and downwardly onto the relatively stationary presser element, said source of illumination being supported by and movable with the movable presser element.

7. In a garment press the combination of a relatively stationary pressing element, a relatively movable pressing element, a source of illumination arranged to illuminate the surface of the lower pressing element, and means automatically operable in the relative movement of the two presser elements for automatically energizing the source of illumination when the pressing elements are separated, said source of illumination being positioned forwardly of the two pressing elements and arranged to direct the rays rearwardly and downwardly onto the relatively stationary presser element.

8. In a garment press the combination of a relatively stationary pressing element, a

- relatively movable pressing element, a source of illumination arranged to illuminate the surface of the lower pressing element, and means automatically operable in the relative 5 movement of the two presser elements for automatically energizing the source of illumination when the pressing elements are separated, said source of illumination being positioned forwardly of the two pressing elements and arranged to direct the rays rearwardly and downwardly onto the relatively stationary presser element, and said source of illumination being supported by and movable with the movable presser element. 10 9. In a garment press the combination of a relatively stationary pressing element, a relatively movable pressing element, a plurality of sources of illumination arranged to illuminate the surface of the lower pressing 20 element, and means automatically operable in the relative movement of the two presser elements for automatically energizing the sources of illumination when the pressing elements are separated, one of said sources 25 of illumination being positioned forwardly of the movable presser element and another being positioned rearwardly thereof with the light rays oppositely directed and toward each other for illuminating the relatively stationary presser element. 30 10. In a garment press the combination of a relatively stationary pressing element, a relatively movable pressing element, a plurality of sources of illumination arranged to 35 illuminate the surface of the lower pressing element, and means automatically operable in the relative movement of the two presser elements for automatically energizing the sources of illumination when the pressing 40 elements are separated, one of said sources of illumination being positioned forwardly of the movable presser element and another being positioned rearwardly thereof with the light rays oppositely directed and toward 45 each other for illuminating the relatively stationary presser element, said forwardly and rearwardly directing sources of illumination being supported by the movable presser element support. 50 11. In a garment press the combination of a relatively stationary pressing element, a relatively movable pressing element, a plurality of sources of illumination arranged to illuminate the surface of the lower pressing 55 element, and means automatically operable in the relative movement of the two presser elements for automatically energizing the sources of illumination when the pressing elements are separated, one of said sources 60 of illumination being positioned forwardly of the movable presser element and another being positioned rearwardly thereof with the light rays oppositely directed and toward each other for illuminating the relatively stationary presser element, said oppositely di- 65 rected sources of illumination being carried by the movable presser element and movable by and with the same. 12. The combination with a pressing machine including the usual lower presser block, upon which a garment, to be pressed, is laid, and the usual upper presser block, of an electrical source of illumination movable with the upper block and positioned to direct its rays onto the surface of the lower presser 70 block when the upper block is elevated, and means, actuated upon movement of the upper presser block to pressing position to open a normally closed circuit to the source of illumination. 75 80 In witness whereof, I have hereunto affixed my signature.
